UNITED STATES PATENT OFFICE

2,561,740

COMBINED CONDUCTOR PLUG AND SPOOL

Earl M. Kennedy, Cuyahoga, Ohio

Application June 11, 1948, Serial No. 32,478

1 Claim. (Cl. 173—361)

1

Outlet plugs for supplying electric current to lamps, lights, electric irons, electrically operated machines, or the like, are usually equipped with electric conductor cords of considerable lengths for the purpose intended. Such cords when in use ordinarily have considerable slack often lying in an unsightly manner on the floor, disposed so as to be in the way, and located where persons may be tripped, causing inadvertent pulling of the plug, and otherwise disadvantageous or a nuisance.

My invention contemplates the provision of a novel plug and spool unit, the plug element of which may be plugged into an ordinary outlet box or socket, and forming a part of the spool element which is designed to lie snugly against a wall or other surface against which the unit is disposed. The spool is adapted to have wound on it any slack portion of the conductor cord, desired to be taken up, and embodies a novel resilient snubbing or clamping portion to engage the cord to prevent displacement of the wound portion thereof when the unit is in use.

The unit of my invention is designed especially to provide a neat and unobjectionable protuberant appearance when in use, as will appear more fully hereinafter.

A preferred embodiment of my invention is illustrated in the accompanying drawing, in which:

Figure 1 is a view in general side elevation showing a combined outlet plug and spool embodying the invention, the lower head of the spool being shown in section as comprising a resilient structure having the snubbing or clamping means for the conductor wire engaged with the latter as when the unit is in use.

Figure 2 is a cross sectional view taken on the line 2—2 of Figure 1, bringing out more clearly the clamping action of the lower resilient head clamping parts in relation to the conductor cord.

Describing my invention specifically in conjunction with the illustration thereof in the accompanying drawings, I note that my combined unit comprises generally a spool having the upper plug head 1 and the lower resilient plug head 2. The upper plug head 1 is equipped with the usual prongs or contact plates 3 with which adjacent ends of the wires of the conductor cord 4 are connected by screws or any other suitable means in the customary manner. From their point of attachment to the terminal prongs 3, the wires of the conductor cord 4 pass through a curved opening in the plug head 1 and emerge from the base of said head at one side of the spool body 5.

which is of shaft-like or cylindrical shape, and extends downwardly from the middle of the lower side of the plug head 1. The spool body 5 is integral with the plug head 1, and in view of the electrical nature of the appliance of my invention, it is contemplated that the parts 1 and 5 shall be made of hard insulation material of rubber, plastic, or other suitable composition.

The spool body 5 is of considerable length, and is formed at its lower end with an annular enlargement or flange 6. For fitting about the flanged end of the body 5 the resilient head 2 of my unit is formed at its upper flat side with a recess extending from said upper flat side and enlarged so as to conform generally with sides of the flange part 6 received in the enlarged portion when the member 2 is assembled with the remaining structure of the unit. By reason of the resilient structure of the lower head 2 of the spool, it is obvious that merely by stretching the material of the said head, the same may be caused to interengage with the flange 6 of the body 5 to establish the interlocking connection between the parts 5 and 2, the portion of the member 2 above the flange 6 snugly fitting the body of the spool to prevent displacement of the member 2 from said body 5. In other words, the recess formed in the upper surface of the resilient head 2 is constricted above the flange 6 of the body 5, thereby to engage over the flange and prevent unauthorized displacement of the part 2 from the part 5.

The plug head 1 is generally of rounded form on its upper and side surfaces, and tapers downwardly toward its outer end. The resilient head 2 is of a general conformation similar to that of the plug head 1 except that the curved surfaces extend in a reverse direction. At their innermost portions the heads 1 and 2 are flat so that they may lie against a wall or baseboard or floor surface, thus disposing the spool body 5 in parallelism with such surface and avoiding any unduly protuberant parts that might be unsightly or be conducive to the accidental displacement of the plug element 1 and its terminal prongs 3 from the outlet box or socket with which the parts 3 are engaged.

At its outermost reduced portion the resilient socket 2 is provided with an inwardly extending recess 7 providing resilient lips or clamping members 8 and an entrance mouth 9 for the introduction into the recess of a portion of the cord 4 for snubbing or clamping action against the cord for purposes to be explained more fully hereinafter.

As previously stated, the conductor cord 4 emerges from the plug head 1 at the lower flat side of the latter and at one side of the spool body 5. From the point of emergence of the cord 4 it may be wound spirally around the spool 5 to an extent such as may be desired to take up whatever slack in the cord is of no use in the employment of the cord as a connector between the plug socket 1 and the lamp, light, or other piece of electrically operated equipment.

As seen in Figure 1, the cord 4 is entirely wrapped around the body of the spool 5 and the extent of unwrapping of the cord from said spool would depend upon the distance at which the electric equipment to be operated by current passing through the cord 4 is disposed in spaced relation to the plug and spool unit of my invention, as will be obvious. The conductor cord 4 is equipped with the usual plug connector 10 for engagement in the socket of a lamp or other piece of electric equipment, along the lines previously described.

Under some conditions, my plug and spool unit may be employed by utilizing the plug head 1 and terminal prongs 3 to connect the unit to a machine or equivalent type of apparatus, and the cord 4 may be then unwound from the spool body 5 to whatever extent necessary to utilize the cord 4 and bring the plug 10 to the proper position for engaging the outlet socket or box located in a wall or like place, the unwinding of the cord, however, being only to such extent as to enable the use of the conductor without having undue slack in the length of the latter.

Having thus described my invention, what I claim as new and desire to secure by Letters Patent of the United States, is:

A combination electric plug and spool unit

comprising a spool body having an integral plug head at one end, electrical terminal prongs extending from said plug head, said plug head and spool body being made of hard insulation material, the spool body being provided at its other end with an annular enlargement flange, a resilient head carried by the end of the spool body having said flange and formed with a flat side having a recess of a size to receive the flange and formed with a constricted portion to fit snugly about the spool body and stretchable over the said flange to interlock the resilient head to the spool body, said resilient head being formed with spaced resilient conductor wire clamping members at a side thereof, and conductor wires being connected to the terminal prongs of the plug head, wrappable about the spool body, and engageable with the clamping members of the resilient head of the unit.
